UNITED STATES PATENT OFFICE.

CHARLES E. MILLER, OF EDGEWOOD, RHODE ISLAND, ASSIGNOR TO PAYTON & KELLEY CO., OF PROVIDENCE, RHODE ISLAND, A CORPORATION OF RHODE ISLAND.

WATCHCASE BEZEL.

Application filed August 21, 1924. Serial No. 733,307.

To all whom it may concern:

Be it known that I, CHARLES E. MILLER, a citizen of the United States, residing at Edgewood, in the county of Providence and 5 State of Rhode Island, have invented certain new and useful Improvements in Watchcase Bezels, of which the following is a specification.

This invention relates to an improved 10 construction of watch case bezels; and has for its object to provide a bezel rim having an inturned flange against which a crystal is seated and the provision of locking members on the flange for firmly pressing the 15 lens against its seat and securing it in position in its frame.

With these and other objects in view, the invention consists of certain novel features of construction, as will be more fully described and particularly pointed out in the 20 appended claims.

In the accompanying drawings:

Figure 1 is a perspective view showing one form of watch to which my improved 25 bezel member is connected.

Figure 2 is a perspective view showing the inner portion of the bezel rim and the crystal locking members therein.

Figure 3 is a perspective view of the bezel 30 frame which fits into the rim and over the lens to support the lens when seated on its flange.

Figure 4 is a sectional elevation illustrating the frame as engaging the edge of 35 the crystal and showing the locking lugs or pins extending through openings in the frame.

Figure 5 is an enlarged view showing the pins or lugs as folded, bent or riveted over 40 the edge of the frame member to force the crystal against its seat.

Figure 6 is a fragmental sectional elevation showing another form of locking member which is adapted to be rotated to bring 45 its head portion over the frame to lock the crystal against its seat.

It is found in watches which have their 50 crystals snapped into their bezels from the outside thereof, that very often their crystals become loosened and snap out of position and so become broken to the great annoyance of the users. To obviate this difficulty, I have formed a bezel rim with in-turned flanges against which the crystal is seated from the inside of the rim and have 55

provided locking means on the rim, which are adapted to be bent, rotated or otherwise moved into position over a bezel frame which extends about the seated portion of the crystal to force the crystal to its seat 60 and so exclude dust, moisture, and other foreign matter and at the same time positively prevent the crystal from becoming loosened and dropping out of its frame; and the following is a detailed description of 65 the present embodiment of my invention showing one means by which these advantageous results may be accomplished:

With reference to the drawing, 10 designates the bezel rim member of my improved 70 construction which corresponds in outline to the shape of a watch and which is provided on its outer edge with an inturned rim 11 of a width sufficiently broad to form a seat at 12 for the edge of a crystal 13. The 75 inner surface of this flange is herein shown as being provided with a set of inwardly-extending bendable lugs 14 for the purpose presently described.

In order to support the edge of the crystal and be able to press it firmly against its seat all around, I have provided a bezel frame 15 the outline of which is preferably that of the rim, and the center portion of which frame is provided with an opening, 80 the shape of which is the same as the opening through the inturned flange of the rim. I have also herein shown slots 16 through this frame, which correspond in shape, size and number to the lugs or pins 14 in the rim 85 whereby upon assembling the parts the crystal is first placed in position against the inner surface of the rim, the frame is next placed upon the edge of the crystal and the pins or lugs are then turned over as at 90 17 to rivet or lock the crystal firmly against its seat in the rim thereby positively preventing the crystal from falling out and becoming broken and also by its close fitting joint it excludes foreign matter from the works of 95 the watch.

In some instances, instead of soldering these lugs 14 to the inner face of the rim flange, I may set a catch member 18, one form 100 of which is shown in Figure 6, which is adapted to be swung over the bezel frame to engage the frame and so force the crystal to its seat on the rim and by this construction whenever it is desired to replace the crystal it is only necessary to swing this head 19 110.

2
back from engagement with its frame to release the frame and crystal.

My improved bezel is very inexpensive to construct and is effective in its operation and by its use the crystal is firmly locked in position in the bezel rim and yet may be removed when desired.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a watch casing, a bezel-rim having an inturned flange about its outer edge, a crystal in said rim seated against the inner

face of said flange, a bezel-frame seated about the edge of the crystal, and a set of bendable fingers on said flange adapted to be bent over into engagement with said frame and bind the crystal edge against said flange.

2. In a watch casing, a bezel-rim having an inturned flange about its outer edge, a crystal in said rim seated against the inner face of said flange, a bezel frame seated about the edge of the crystal, and a set of bendable lugs fixed to the inner face of said flange to extend through corresponding openings in said frame and adapted to be bent thereover to bind and lock the crystal against the frame adjacent its flange.
